UNITED STATES PATENT OFFICE.

WILLIAM C. HEINDEL, OF EAST ORANGE, NEW JERSEY, ASSIGNEE TO THE WHITEHEAD & HOAG COMPANY, OF NEWARK, NEW JERSEY, A CORPORATION OF NEW JERSEY.

SPOUT ATTACHMENT FOR POWDER-CONTAINING RECEPTACLES.

1,239,181.

Specification of Letters Patent. Patented Sept. 4, 1917.

Application filed January 22, 1917. Serial No. 143,712.

To all whom it may concern:

Be it known that I, WILLIAM C. HEINDEL, a citizen of the United States of America, and resident of East Orange, in the county of Essex, in the State of New Jersey, have invented new and useful Improvements in Spout Attachments for Powder-Containing Receptacles, of which the following, taken in connection with the accompanying drawings, is a full, clear, and exact description.

This invention relates to powder-containing receptacles and has more particular reference to a spout attachment therefor.

The object of the invention is to provide, preferably the cover of the box containing powder, such as, salt or other powdered material, with an attachment which will form normally no obstruction to the exterior of the box or cover but which may be brought into use readily when it is desired to transfer the contents of the receptacle into some other receptacle, as for illustration, salt into a salt-cellar. I do not wish it understood, however, that the attachment must be secured to the cover of the receptacle. As a matter of fact, it may be secured to the bottom of the receptacle or to the side but it would be more convenient to secure it to the cover, as shown in the drawings.

The invention, therefore, consists in the several new and novel features of construction and operation hereinafter described and specifically set forth in the claims hereunto annexed.

Referring to the drawings which form a part of the specification,—

Figure 1 is a plan view of a box for holding powdered material showing the cover thereon and is provided with a spout attachment.

Fig. 2 is a cross section of the upper portion of the receptacle through the spout attachment, showing the spout in dotted lines, raised to the position which it would occupy when in use.

Fig. 3 is a part of the cover showing the opening therein for receiving the spout attachment.

Fig. 4 is a detached view of the spout attachment.

Referring now to the drawings,—

—A— is a box suitable for holding salt

or other material in powdered form and may be of any desired form and is provided with a cover —B— and with an opening —C—, said opening having two sides parallel and the opposite sides converging as shown at —a— and —a'— for the purpose which will be hereinafter described. —D— for convenience may be called the spout attachment as a whole and is preferably made of celluloid or other suitable material which, of course, may include paper, aluminum or any material adapted for the purpose in hand.

This spout comprises a base —b— having a tongue or extending portion as shown, acting as a stop when spout is closed, one end being slightly reduced in size as shown at —b'—. Extending from said base are side walls —c— and —c'— preferably constructed integral with the base. One edge of the side walls is curved as shown at —d— and the rear edge of said walls preferably extends at an angle to the plane of the base —b— as shown at —e— and —e'—.

—f— and —f'— are recesses in the side walls located at one end of the base, as shown, and —g— and —g'— are lugs at the lower edge of the walls and —h— and —h'— are notches in the curved edge of the side walls, all of which parts are for a purpose which will be presently described.

When it is desired to insert the spout attachment into one of the walls of the receptacle, as for illustration, the cover, as shown in Fig. 3, the spout is placed in a position

from the opening so that the base will stand in substantially a vertical position. The spout is then inserted into the opening until the notches —h— and —h'— engage with one of the walls of the opening —C—.

The spout is then moved slightly toward the notched side and the opposite end is dropped sufficiently so that the end of the base —b—

will rest upon the tongue —a'— and the recesses —f— and —f'— will engage the walls of the opening —C— at which time

the spout is moved slightly in that direction and it then forms a hinge connection upon which the spout may move down to the position shown in Fig. 2 when not in use or up to the position shown in the dotted lines in

Fig. 2 when it is desired to use it as a spout for allowing the powdered material to flow

out of the box. The outer end of the base —*b*— has an extending portion —*b'*— which allows it to rest upon the wall —*a*— of the opening —*C*— so as to prevent its being 5 forced down into the receptacle.

The lugs —*g*— and —*g'*— when the spout is raised to a position shown in dotted lines in Fig. 2, engage with the inner face of the receptacle so as to prevent its being 10 withdrawn.

What I claim is:—

1. An article of manufacture of the character described comprising in combination a receptacle having an opening in the wall 15 thereof, a portion of the wall projecting inwardly to form a ledge, a spout movably mounted in said opening, said spout having a base of a size to cover said opening and ledge and having pendant side walls extending 20 at substantially right angles to said base, a recess in each side wall at the rear of the base for receiving a wall of said opening, and a notch in the front edge of each side wall of a width sufficient to receive a wall 25 of said opening.

2. An article of manufacture of the character described comprising in combination a receptacle having an opening in the wall thereof, a portion of the wall projecting inwardly to form a ledge, a spout movably mounted in said opening, said spout having a base of a size to cover said opening and ledge and having pendant side walls extending 30 at substantially right angles to said base, a recess in each side wall at the rear of the base for receiving a wall of said opening, a notch in the front edge of each side wall of a width sufficient to receive a wall of 35 said opening, and lugs projecting outwardly from each side wall at the rear of its respective notch for limiting the movement of 40

the spout through the opening in said receptacle.

3. The combination with a receptacle having an opening in the wall thereof, of a 45 spout movably mounted in said opening, said spout comprising a pair of substantially parallel side walls, a base connecting the side walls for a portion of their length, a recess in each side wall at the rear of the 50 base, the upper edge of the side wall at the rear of the base lying in a plane spaced from the plane of the lower surface of the base a distance substantially equal to the thickness of the adjacent wall of the receptacle, said 55 side walls having an arcuate front edge, a notch in the front edge of each side wall, and a lug projecting outwardly from each side wall at the rear of its respective notch.

4. An attachable pouring spout comprising 60 a pair of substantially parallel side walls, a base connecting the side walls for a portion of their length, a recess in each side wall at the rear of the base, said side walls having an arcuate front edge, and a notch 65 in the arcuate edge of each side wall.

5. An attachable pouring spout comprising 70 a pair of substantially parallel side walls, a base connecting the side walls for a portion of their length, a recess in each side wall at the rear of the base, said side walls having an arcuate front edge, a notch in the arcuate edge of each side wall, and a lug on each side wall projecting outwardly 75 therefrom at the rear of its respective notch.

In witness whereof I have hereunto set my hand this 12th day of January, 1917.

WILLIAM C. HEINDL.

Witnesses:

JAMES CHARLES KELLY,
CHARLES W. MERCIER.
